UNITED STATES PATENT OFFICE.

CLARENCE L. JOHNSTON, OF OAKLAND, CALIFORNIA, ASSIGNOR TO MARCHANT CALCULATING MACHINE COMPANY, OF OAKLAND, CALIFORNIA, A CORPORATION OF CALIFORNIA.

CALCULATING MACHINE.

Application filed September 28, 1921. Serial No. 503,903.

To all whom it may concern:

Be it known that I, CLARENCE L. JOHNSTON, a citizen of the United States, and a resident of Oakland, county of Alameda, 5 and State of California, have invented certain new and useful Improvements in Calculating Machines, of which the following is a specification.

The invention relates to calculating machines in which the figure discs of the registering mechanism are arranged on a carriage, which is disposed in parallel displaceable relation to the actuating mechanism, for the purpose of making direct action of 15 the units of the actuating mechanism on figure discs of different denomination possible. For this purpose, the carriage is movable longitudinally in a step-by-step motion and the present invention relates to means 20 for shifting the carriage longitudinally, either in a unit step motion or in a free motion, in either direction.

An object of the invention is to provide a carriage moving mechanism which is positive and practically noiseless in operation.

Another object of the invention is to provide a carriage moving mechanism which prevents overthrow of the carriage.

A further object of the invention is to 30 provide a carriage moving mechanism in which the pressure applied to move the carriage is exerted in the direction in which the carriage is to be moved.

The invention possesses other advantageous features, some of which, with the foregoing, will be set forth at length in the following description, where I shall outline in full, that form of the invention which I have selected for illustration in the drawings accompanying and forming part of the present specification. In said drawings I have shown one form of the invention and a modification thereof, but it is to be understood that I do not limit myself to such forms, since the invention, as set forth in the claims, may be embodied in a plurality of other forms.

Referring to said drawings:—

Figure 1 is a front elevation of the base 50 of a calculating machine with the carriage mounted thereon and the shift of my invention mounted thereon.

Fig. 2 is an elevation of the shifting mechanism with the front plate removed, 55 showing the carriage.

Fig. 3 is a cross section taken on the line 3—3, of Fig. 2.

Fig. 4 is a plan view of one of the locking dogs.

Fig. 5 is a longitudinal vertical section 60 through a modified form of apparatus.

Fig. 6 is a section taken on the line 6—6, Fig. 5.

Figs. 7, 8 and 9 are diagrammatic representations showing the locking dogs in their 65 different positions.

Fig. 10 is a perspective view of the shift shown in Figs. 5 and 6.

Fig. 11 is an elevation of one form of the calculating machine provided with the shift 70 of Fig. 10.

The calculating machine shown in the drawings, and which is one type of machine to which my invention is applicable, comprises a base 2 on which the actuating mechanism is arranged and on which the carriage 3 is slidably mounted in longitudinal displaceable relation, so that the figure wheels of the registering mechanism on the carriage may be moved into co-operative relation with different units of the actuating or counting mechanism. The carriage is movable in a step-by-step movement, the length of each step being equal to the spacing of the corresponding parts of the figure discs, 80 so that the figure discs are moved at each step to bring the discs of the next denomination into co-operative relation with the respective actuating units.

The shifting device of my invention, may 90 be fixed on the base and engage the carriage, as shown in Figs. 1, 2 and 3 or it may be fixed on the carriage and engage the base, as shown in Figs. 5 and 6, whichever may 95 be the more desirable. In the operation of calculating machines, the carriage is shiftable in either direction either in a step-by-step movement or freely, depending upon the nature of the calculating being performed and means are provided for permitting either of these motions being obtained. It is essential in the step-by-step movement, 100 that the carriage be moved a unit distance only, at each operation of the shifting mechanism and since this movement is performed rapidly by the operator, it is essential that there be no overthrow of the carriage, that is, that the carriage move only one unit distance. The shift of my invention is particularly designed to prevent overthrow, re- 110

gardless of the speed at which the carriage is shifted.

For this purpose I employ two spring pressed dogs or latches, mounted on one element, either the carriage or the base, which co-operate with a rack on the complementary element, either the base or the carriage. The dogs are arranged so that one of them springs into a notch in the rack while the movement of the carriage through the unit distance is taking place, so that it is in position to arrest the motion of the carriage at the end of the unit distance of travel. At this point, the second dog springs into engagement with a shoulder on the rack preventing any backward movement of the carriage, thus holding the carriage accurately positioned. The dogs may be arranged adjacent each other, so that they both spring into the same notch in the rack or they may be spaced apart so that they spring into spaced notches.

In the construction shown in Figs. 1, 2 and 3, the dogs are spaced apart and are mounted on the base of the machine and co-operate with a rack on the carriage. Formed on or secured to the carriage 3, preferably along its lower front edge, is a stop rack 4 composed of rectangular teeth 5, preferably of less width than the notches between the teeth. The tooth pitch, or the distance between the center lines of two adjacent teeth is equal to the unit distance of the step-by-step movement. Pivoted to the base and disposed below the rack 4 are two spring pressed dogs 6 and 7, normally pressed upward into engagement with the rack. The dogs are so positioned that normally, one dog 6 lies in engagement with one side of one tooth and the other dog 7 lies in engagement with the other side of another tooth, so that the carriage is firmly locked and securely held in position by the two dogs, the dog 6 preventing movement to the right and the dog 7 preventing movement to the left. The dogs are provided with oppositely inclined or bevelled faces 8, so that each dog operates to prevent movement in one direction only, that is, when dog 6 is depressed, the carriage may be freely moved to the right and when dog 7 is depressed, it may be freely moved to the left. The dogs are provided with knobs 6^a and 7^a lying in front of the front plate 9, so that either dog may be depressed to permit free movement of the carriage in the desired direction. During such movement the other dog rides under the teeth on the rack 4.

Means are provided for moving the carriage longitudinally in either direction in a step-by-step movement. Pivoted intermediate their ends to the front plate 9 are two levers 13—14 co-operatively engaging the dogs 6 and 7, each lever being movable in

one direction only from its normal position. At their lower ends the levers engage spring pressed retreating pins 15 disposed longitudinally in the dogs. The pins are bevelled on their rear faces and the lower ends of the levers are bevelled on their front faces, so that in one direction of movement the lever depresses the dog out of engagement with the rack and in the other direction of movement, passes and pushes back the pin without depressing the dog. When the lever 13, for instance, is moved clockwise, the dog 6 is depressed and, as the lever moves backward to normal position, the dog remains immovable. The upper ends of the levers are held spread apart in their normal positions by a compression spring 16 interposed between the upper ends of the levers and surrounding a bar 17 passing loosely through eyes on the levers.

Means are provided for causing movement of either lever to move the carriage a unit distance in the direction of movement of the upper end of the lever. Pivoted to each lever, adjacent the upper end thereof, is a downwardly spring pressed finger 18 which engages the upwardly faced advancing rack 19 on the carriage, the pitch of the teeth of the rack being equal to the unit distance of movement. When the lever is moved from its normal position, the holding dog is released, the finger engages and moves the rack and the holding dog springs back into engagement with its rack prior to the end of the unit movement. Disposed between the fingers is a finger guide rail 21 having inclined portions 22 over which the ends of the fingers ride during part of the movement of the levers. On the forward movement of a lever, the finger rides down over the guide rail into engagement with the rack 19 and on the backward movement of the lever, the finger rides up on the guide rail, out of engagement with the rack, so that normally the fingers are not engaged with the advancing rack.

The levers are moved to release and advance the carriage, by a slide plate 23 mounted on the front plate 9. The slide plate is provided with a flange overlying the levers, which flange is provided with a slot through which the upper ends of the levers extend and against the ends of which slot the levers bear. The slide is provided on its front face with one or more tongues or projections 24, which are engaged by the finger of the operator for moving the carriage. Movement of the slide to the right, rocks lever 13, depresses dog 6 and advances the carriage a step toward the right, and movement of the slide to the left similarly causes movement of the carriage one step to the left.

In the construction shown in Figs. 5 and 6, the carriage shifting device is mounted on

and moves with the carriage, and while the specific construction of the device is different from that shown in the prior figures, its generic construction, mode of operation and advantages are substantially identical. In this embodiment, the stop rack 26 is fixed to the base of the machine and is provided with teeth 27 having the same pitch as the rack 4. The rack 26 is engaged by two spring pressed dogs 28 and 29, having bevelled upper faces and arranged in juxtaposition, so that they both seat in one notch in the rack, the dog 28 preventing movement of the carriage to the left and the dog 29 preventing movement to the right. In operation, actuation of the shift removes both dogs from the rack and releases them so that they spring into the position indicated in Fig. 7. Movement of the shift toward the right permits the dog 29 to spring into the notch between teeth, as shown in Fig. 8, so that it is in position to engage the next tooth and halt the movement of the carriage. When the carriage reaches the end of its unit movement toward the right, the dog 28 springs into the notch, as shown in Fig. 9, locking the carriage against movement to the left, so that the carriage is accurately locked in position against movement in either direction. Means are provided for simultaneously depressing the dogs and shifting the carriage by the application of pressure in the direction in which it is desired to move the carriage. Secured to the carriage at the front thereof, is a casing 31, in which are mounted spring retracted levers 32-33, the upper ends of which extend through and engage the ends of a slot 34 in the slide 35 mounted on the casing. Pivoted to the levers 32-33 are latches 36-37, which normally rest on pins 38-39 on the bent levers 41-42, pivoted to the casing. The lower arms of the levers 41-42 overlie the horizontal arms of the dogs 28 and 29, so that when either lever 41 or 42 is rocked on its pivot, the dogs are depressed from engagement with the stop rack. The levers 41 and 42 are rocked on their pivots by engagement of the shoulders 43-44 on the latches 36-37 with the pins 38-39 on the levers. Journalled on the carriage intermediate the levers 41-42, is a star wheel 45, which lies in the path of the latches 36 and 37, so that as the lever 32, for instance, is moved to the right, the end of the latch 36 engages the star wheel which is rotated by movement of the carriage. During its rotation, the next lower tooth on the star wheel presses upward on the latch 36 and moves the shoulder thereon out of engagement with the pin 38 on the lever 41, thus releasing the lever and the dogs. The same action occurs when the lever 33 is rocked to the left. Secured to the shaft of the star wheel, is a gear 46, rotatable with the star wheel and engaging an advancing

rack 47 on the base of the machine, so that the carriage is moved in time with rotation of the star wheel.

Assuming that it is desirable to move the carriage a unit distance to the right, pressure in that direction is exerted on the tongue 48 of the slide 35. This shifts the slide to the right, rocks lever 32 and lever 38, depressing the dogs 28 and 29 so that the exerted pressure moves the carriage. The initial movement of the carriage rotates the star wheel sufficiently to release the latch 36 from the pin 38, permitting the dogs to spring upwardly, into substantially the position shown in Fig. 7 and the further movement of the carriage causes the dogs to assume the positions shown in Figs. 8 and 9. When it is desired to shift the carriage freely in either direction, the pressure of the finger is exerted directly against the upwardly projecting end of the proper lever 41 or 42, depending upon the desired direction of movement.

I claim:

1. In a calculating machine, a frame, a carriage movable on said frame and means for locking the carriage in fixed position comprising a rack and two independently movable dogs normally in engagement with said rack. 90
2. In a calculating machine, a frame, a carriage movable on said frame and means for locking the carriage in fixed position comprising a rack and two independently movable dogs adapted to simultaneously and positively engage different teeth on said rack. 100
3. In a calculating machine, a frame, a carriage movable on said frame and means for locking the carriage in fixed position comprising a rack and two independently movable dogs movable successively into engagement with said rack and both normally engaging said rack. 105
4. In a calculating machine, a frame, a carriage movable on said frame and means for locking the carriage in fixed position comprising a rack and two independently movable dogs movable into engagement with said rack, one of said dogs operating to halt movement of the carriage in one direction and the other operating to prevent movement of the carriage in the opposite direction. 110
5. In a calculating machine, a frame, a carriage movable on said frame and means for locking the carriage in fixed position comprising a rack, a dog movable into engagement with the rack to halt movement in one direction and a second dog movable subsequently into engagement with the rack to prevent movement in the opposite direction both dogs being normally in engagement with the rack. 120
6. In a calculating machine, a frame, a 130

carriage movable on said frame, a rack co-operating with said carriage, two independently movable dogs co-operating with said rack, one of said dogs preventing movement of the carriage to the right and the other preventing movement to the left, means operative by the application of force to move the carriage in one direction to remove from the rack the dog, preventing movement in that direction and means operative by the movement of the carriage for releasing said dog to permit it to engage the rack before the carriage reaches the end of its movement.

7. In a calculating machine, a frame, a carriage movable on said frame, a rack co-operating with said carriage, a spring pressed dog engaging a tooth in said rack to prevent movement of the carriage in one direction and a spring pressed dog engaging another tooth in said rack to prevent movement of the carriage in the opposite direction, whereby the carriage is held firmly against movement in either direction.

8. In a calculating machine, a frame, a carriage movable on said frame, a rack co-operating with said carriage, a spring pressed dog engaging a tooth in said rack to prevent movement of the carriage in one direction and a spring pressed dog engaging another tooth in said rack to prevent movement of the carriage in the opposite direction, whereby the carriage is held firmly against movement in either direction and means for simultaneously moving both dogs from engagement with said rack whereby the carriage may be moved freely in either direction.

9. In a calculating machine, a frame, a carriage movable on said frame, a rack co-operating with said carriage, a spring pressed bevelled dog engaging a tooth on said rack to prevent movement of the carriage to the left only, a second spring pressed bevelled dog engaging a tooth on said rack to prevent movement of the carriage to the right only and means for removing one of said dogs from the rack whereby the carriage may be moved freely in one direction.

10. In a calculating machine, a frame, a carriage movable on said frame, a rack co-operating with said carriage, two spring pressed dogs engaging said rack, each dog operating to prevent movement of the carriage in one direction only, a lever associated with each dog for moving the dog out of engagement with the rack and means on the lever co-operating with the carriage for simultaneously moving the carriage.

11. In a calculating machine, a frame, a carriage movable on said frame, a rack associated with said carriage, a dog engaging

said rack to prevent movement of the carriage in one direction, a second dog engaging the rack to prevent movement of the carriage in the opposite direction, a lever co-operating with each dog to move the dog from engagement with the rack and means on each lever for moving the carriage in one direction, the dog being released from the lever before the lever reaches the end of its stroke, to permit the dog to engage the rack.

12. In a calculating machine, a frame, a carriage movable on said frame, a rack associated with said carriage, a dog engaging said rack to prevent movement of the carriage in one direction, a second dog engaging the rack to prevent movement of the carriage in the opposite direction, a lever co-operating with each dog, movement of a lever in the direction in which the carriage is to be moved serving to remove the associated dog from the rack and to release the dog to permit it to engage the rack before the lever reaches the end of its stroke and means on the lever for moving the carriage.

13. In a calculating machine, a frame, a carriage movable on said frame, a rack associated with said carriage, a dog engaging said rack to prevent movement of the carriage in one direction, a second dog engaging the rack to prevent movement of the carriage in the opposite direction, a lever co-operating with each dog, movement of a lever in the direction in which the carriage is to be moved serving to remove the associated dog from the rack and to release the dog to permit it to engage the rack before the lever reaches the end of its stroke, a second rack associated with said carriage and means on the lever arranged to engage said second rack to move the carriage.

14. In a calculating machine, a frame, a carriage movable on said frame, a rack associated with said carriage, a dog engaging said rack to prevent movement of the carriage in one direction, a second dog engaging the rack to prevent movement of the carriage in the opposite direction, a lever co-operating with each dog, movement of a lever in the direction in which the carriage is to be moved serving to remove the associated dog from the rack and to release the dog to permit it to engage the rack before the lever reaches the end of its stroke, a second rack associated with said carriage, means on the lever arranged to engage said second rack to move the carriage and an actuating means movable in opposite directions from a normal position co-operating with said levers.

In testimony whereof, I have hereunto set my hand.

CLARENCE L. JOHNSTON.
